U.S. Cl. D7—12

FIG. 1

FIG. 2

FIG. 3

FIG. 4

FIG. 1 is a side elevational view of a goblet or a similar article showing my new design;

FIG. 2 is a top view thereof;

FIG. 3 is a bottom view thereof; and

FIG. 4 is a side elevational view showing my new design in the dimensions and shape of a sherbet cup similar to that shown in FIG. 1.

The flowers visible through the top interior walls of the goblet have been omitted from FIG. 2 for convenience of illustration.

The sides of FIGS. 1 and 4 not shown in the drawings are substantially the same as the sides shown.

This application is a division of application Ser. No. 380,272 filed July 18, 1973, and now Pat. No. D. 237,031.

I claim:

The ornamental design for a goblet or similar article, substantially as shown and described.
